UNITED STATES PATENT OFFICE.

CHARLES D. HOLMES, OF WEST MYSTIC, CONNECTICUT.

LIFE-BOAT.

1,119,755.

Specification of Letters Patent.

Patented Dec. 1, 1914

Application filed March 10, 1914. Serial No. 823,809.

To all whom it may concern:

Be it known that I, CHARLES D. HOLMES, a citizen of the United States, residing at West Mystic, in the county of New London, 5 in the State of Connecticut, have invented a certain new and useful Improvement in Life-Boats, of which the following is a specification, reference being had to the accompanying drawings, in which—

10 Figure 1 is a side elevation of a lifeboat embodying my present improvements and Fig. 2 is mainly a longitudinal, central, vertical, sectional view of said boat. Fig. 3 is a plan of said boat with the major portion 15 of the deck removed. Fig. 4 is a transverse, vertical, sectional view taken on the line 4—4 of Fig. 1, looking forward, Fig. 5 is a similar view taken on the line 5—5 of Fig. 1 looking astern and Fig. 6 is a similar view 20 taken on the line 6—6 of said Fig. 1 looking astern. Fig. 7 is a relatively enlarged, 25 sectional, view of the hood which protects the exposed end of a breathing tube by means of which fresh air may be introduced into the cabin whenever it is unsafe or inconvenient to have the port-holes or companion-way door open. In Fig. 8 I have shown, in section, and somewhat enlarged, a portion 30 of the double shell or skin of the boat. Fig. 9 is a relatively enlarged, sectional, view of an automatic safety valve located in the breathing tube already referred to.

My object is to provide a motor lifeboat 35 that is non-sinkable, self-righting and self-bailing, in which special provision is made for the protection of the engine as well as for the passengers housed in the cabin, also for the complete separation of the engine and fuel from the cabin.

40 Included in my improvements is the special location of arrangement of the cabin, the cockpit and engine room whereby every foot of space in the boat is made available; my immediate purpose being to provide a 45 lifeboat which, having been launched from a vessel, will be specially adapted for housing comfortably a large number of passengers and which may run under its own power several days, if necessary, even in 50 rough seas.

Referring to the annexed drawings, the 55 numeral 10 indicates as a whole the hull of the boat, said hull being formed, as here shown, of an inner shell 10^a preferably of metal, and an outer shell of two plankings 10^b—10^c and an interposed sheet 10^d of oiled,

or chemically treated, canvas, thus providing a practically indestructible hull with an air space which will give great buoyancy to the boat without the aid of special air compartments, or air-tight bulk-heads, which would take up a considerable part of the space which is available for passengers and storage of provisions under my present improved arrangement.

The engine-room, denoted by the numeral 11, is located at the after end of the boat, is covered by a tight deck 12 and is cut off from the cockpit 13 by a bulk-head partition 14 which extends from the deck 12 down to the cockpit floor 15. From the said cockpit floor a special bulk-head partition 16 extends downward and athwart-ships to the inner shell 10^a; said bulk-head 16 being set under the flooring of the cock-pit, out of 60 vertical alinement with the main bulk-head 14 in order to provide additional room in the engine compartment and, incidentally, room for a compressed air tank 17 which may be utilized in starting the engine and 65 for blowing a whistle if desired. The engine 18 is mounted upon a substantial bed 19 of cement which insures stability as well as protection from fires which might result from "back-firing" or other causes; the described construction providing an engine 70 compartment with air-tight and water-tight metallic walls and which is completely isolated from the cabin, which latter is indicated by the numeral 20 and is located well 75 forward in the hull of the boat.

The bulk-head 21, which forms the after end wall of the cabin, extends from the cabin housing 22 downward to the cockpit floor 15 already referred to, and the cabin 80 extends aft, under the cockpit floor 15, to the bulk-head 16, thus providing valuable storage space for provisions or luggage or, preferably, sleeping berths 23 for two or more persons on each side of the boat.

The cabin may be entered from the cockpit through tight-fitting doors 24 and the engine compartment may be entered through a tight-closing door 25.

My present plan contemplates the provision of means, operable from the cockpit, whereby the engine may be started, stopped, regulated and otherwise governed, and the steering of the boat may be also accomplished from the cockpit; my purpose being 105 to provide a boat in which the passengers 110 may be shut into a practically water-tight

cabin during rough weather, or during the launching operation, and the boat may be readily handled by the exposure of one man only. In order to ventilate the cabin when it is thus closed, or is partly submerged, I provide a "breathing tube" 26 which extends, as here shown, from the highest point of the cabin downward to, or nearly to, the flooring of the cabin; the said tube being provided with a cut-off valve 27 having a pendulous handle 27^a, the valve being so constructed that it remains open for the admission of air so long as the boat is in an approximate level position but is closed by the swaying of the weighted handle whenever the boat capsizes or is careened sufficiently to carry the exposed end of the breathing tube under water; preventing the water from passing downward in pipe 26 below the cut-off valve 27, the construction and operation of said valve being best understood by reference to Fig. 9 of the drawings.

The cabin is provided on opposite sides with berths 28 which may be used for sleeping purposes by night and as seats during the day and the space under these berths may be utilized for air tanks, if so desired, or for storage purposes. The interior of the cabin is completely padded so that, in the event that the boat is overturned during the launching operation, or by reason of extremely rough weather, the passengers huddled together in the closed cabin will be protected against injury so far as is possible. Under the seats 29 in the cockpit tanks 30 are provided for the safe storage of a large supply of fuel. The cockpit floor 15 is located somewhat above the water line and scuppers 31, leading outward therefrom, are provided so that all water taken inboard by the over-turning, or careening, of the boat, will find its way overboard when the boat rights itself. Forward of the cabin is a toilet compartment 32 which is separated from the cabin by a partition 33 and a door 34.

My described improvements provide a lifeboat that is driven by its own power, with separated air-tight and water-tight engine and cabin compartments, either of which will furnish a degree of buoyancy sufficient to float the boat if the other is punctured; the engine and fuel tanks are isolated from the cabin; the boat is formed with a double hull so that, if the outer shell is broken through and the inner shell indented, the boat will still remain safe and serviceable; the engine is set in cement with special regard to safety from fire, and the space between the outer and inner shells of the hull provides air-tight compartments which serve to give buoyancy to the boat without having to utilize the more valuable space in the cabin for special air tanks. 65

Having thus described my invention, I claim:—

1. A motor boat comprising a hull formed with an outer shell and an inner shell, with air space between said shells, a cabin, an engine compartment, a cockpit between said cabin and engine compartment, the floor of the cockpit being above the water line, and a bulkhead below the cockpit floor and separating the cabin from the engine compartment. 70

2. In a motor boat, in combination, a cabin, an engine compartment, a cockpit floor above the water line, said cabin extending aft under the cockpit floor, and a bulkhead separating the cabin from the engine compartment. 75

3. In a motor lifeboat, in combination, a cabin, an engine compartment, a cockpit with floor above the water line between said cabin and engine compartment, said engine compartment extending forward under the cockpit floor, and a bulkhead separating said extension from the cabin. 80

CHARLES D. HOLMES.
